UNITED STATES PATENT OFFICE.

GREGORY JOHN SPOHRER, OF EAST ORANGE, NEW JERSEY.

DISPENSER FOR COMPRESSED AIR.

1,395,368.

Specification of Letters Patent.

Patented Nov. 1, 1921.

Application filed November 6, 1919. Serial No. 336,132.

To all whom it may concern:

Be it known that I, GREGORY J. SPOHRER, a citizen of the United States, residing at East Orange, in the county of Essex, State 5 of New Jersey, have invented certain new and useful Improvements in Dispensers for Compressed Air; and I do hereby declare the following to be a full, clear, and exact description of the invention, such as will 10 enable others skilled in the art to which it appertains to make and use the same.

This invention relates to the dispensing of compressed air and has particular reference to air used in inflating automobile tires, 15 although the apparatus hereinafter described, may obviously be employed in handling gases other than air, which are supplied under pressure.

Automobile tires of different sizes require 20 inflation to varying pressures, in accordance with more or less standardized practice, and the introduction of air to a tire at a pressure, exceeding that for which it is designed, may cause serious injury thereto. It is customary 25 at garages to maintain a supply of air, under pressure, for use of customers. The air is usually held in a suitable tank at a pressure of upward to two-hundred and fifty pounds 30 per square inch. Obviously, the careless use of air at such a pressure in inflating tires intended to receive air at much lower pressures is likely to result in an irreparable damage. It is the object of the present invention to provide a dispenser for air under 35 pressure which permits the user to determine, in advance, the exact pressure at which the air will be delivered to the tire and which will prevent the delivery of air at higher pressures, regardless of the pressure at which 40 the supply of air is maintained.

A further object of my invention is to embody an apparatus of the character described in a practical form which adapts it to employment for its intended purpose and 45 for use by persons unfamiliar with this mechanism without possible damage thereto.

Further objects and advantages of the invention will be apparent as it is better understood by reference to the following 50 specification, when read in connection with the accompanying drawing illustrating the preferred embodiment of the invention, in which—

Figure 1 is a view in elevation of the apparatus; Fig. 2 is a vertical transverse section therethrough;

Fig. 3 is a detail in horizontal section, illustrating the controlling valve;

Fig. 4 is a similar view in vertical section; 60

Fig. 5 is a detail, in section, illustrating the reel for the air hose.

Referring to the drawing, 5 indicates a suitable standard, preferably hollow, which may carry at its top, for example, an illuminated sign 6 bearing the words "Free air," the name of the proprietor of the garage, or any suitable subject matter. Near its upper end, the standard supports a hollow spindle 7 in bearings 8. The spindle 7 carries a reel 70 9 for an air hose 10, the latter having a coupling 11 through which the hose is connected to the tire nipple. The inside width of the reel preferably corresponds to the diameter of the hose, and the edges of the 75 reel are flared. The other end of the hose passes through an opening in the spindle 7 and thence longitudinally to the flared end 12 thereof. The reel 9 is preferably enclosed by a casing 13 having an opening 14 80 through which the hose is withdrawn. A flared flange 15 surrounds the opening 14 so that the hose may be pulled in any direction from the reel. A drum 17 is fast to the spindle 7 within the standard 5 and a 85 weight 18 is secured to the end of a cord or chain 19 which is adapted to be wound on the drum 17 when the hose 10 is withdrawn from the reel 9. When the hose is released, the weight 18 rotates the spindle 7 to rewind 90 the hose, so that the latter is normally compactly arranged and preserved against injury.

A bracket 20 projecting from the standard 5 supports a valve casing 21 having an inlet 95 passage 22 for air under pressure, the air being conveyed by a pipe 23 from a source of supply such as a tank. The passage 22 communicates with a duct 24 which terminates in a seat 25 within the casing 21, 100 and a valve 26 on a yoke 27 is normally held in engagement with the seat by a spring 28 disposed between the end of the yoke and a cap 29, which is threadedly disposed in an opening at one end of the casing 21. A stem 105 30 connected to the yoke is movable in a guideway 31, provided therefor in the cap 29. The yoke 27 is connected to a diaphragm 32 which is secured at its edges by a cap 33 threadedly engaging the casing 21 and a 110 spring 34 is disposed between the diaphragm 32 and a plug 35 threadedly arranged in the

cap 33, so that rotation of the plug varies the tension which the spring 34 exerts upon the diaphragm 32. A projection 36' on the diaphragm serves to prevent lateral displacement of the spring 34. An outlet 36 from the casing 21 is connected to the hose 10 which extends beyond the flared end 12 for this purpose and is preferably coiled as indicated in the drawing so that the reel may 10 rotate without resistance. As will be readily understood, gas from the source of supply will be permitted to pass the valve 26 until the pressure within the casing 21 and the connections to the tire to be inflated, overbalances the tension of the spring 34 and thereby causes the valve 26 to engage the seat 25.

To allow adjustment of the tension of the spring 34 and permit the delivery of gas 20 to a predetermined pressure, an indicator 38 is supported on a spindle 39 projecting from the standard 5 and is connected to a collar 40 carrying a gear 41 which meshes with a pinion 42 having a clutch 43. Pins 25 44 on the stem 45' of the plug 45 are engaged by the clutch 43 so that rotation of indicator 38 transmits a corresponding movement to the plug 45. A dial 46 is supported on the spindle 39 and a spring 47 is 30 fastened to the rear face thereof and to the collar 40. Thus, unless held in the desired position, the indicator 38 is returned to the zero position, thereby releasing the tension of the spring 34 and permitting the valve 35 26 to seat and prevent escape of gas to the casing 21. The dial 46 is provided with graduations 48 indicating numerically the pressure in pounds, and by movement of the indicator 38 to the graduation corresponding 40 to the desired air pressure, the tension of the spring 34 is correspondingly increased to force the valve 26 from its seat and permit the passage of air through the 45 connections to the tire with which the hose 10 has been previously coupled.

To facilitate retention of the indicator 38 in the desired position, the dial is provided with a plurality of openings 49 disposed adjacent the graduations and a pin 50 is supported on the indicator 38 for engagement with the selected opening 49. A spring 51 surrounding the pin 50 within a suitable housing 52 normally holds the pin from engagement with the dial and a knob 53 on 55 the end of the pin permits the operator to compress the spring 51. As soon as the operator releases the knob 53, the pin 50 is withdrawn from the opening 49 with which it is engaged and the spring 47 returns the indicator 38 to zero position.

From the foregoing description, it will be apparent that, under normal conditions, the hose 10 is wound upon its reel and escape of air is prevented because of the tension of the spring 34 is relieved and no gas

is permitted to pass the valve 26. The standard pressures for tires of different sizes may be advantageously delineated upon the dial 46 and the operator knowing the size of the tire may, by grasping the indicator 38, move it to the corresponding graduation 48. This movement tensions the spring 34 and permits the passage of air into the casing 21 and thence to the tire. The operator thereafter holds the indicator 75 38 in the desired position by engaging the pin 50 with the corresponding opening 49 until the desired inflation has been accomplished. If the operator continues to hold the indicator 38, no damage to the tire results, because the air is automatically cut off as soon as the pressure in the tire overbalances the tension of the spring 34. If the operator, on the other hand, releases the indicator 38 before inflation is complete, he 80 will, upon determining that more air is required, return the indicator to the same point upon the dial and will hold it there until the desired inflation is accomplished.

The apparatus described enables an unskilled operator to inflate automobile tires to exactly the required degree, without employing a pressure gage and without danger of over inflation, when using air from a tank in which it is maintained under relatively high pressure. The apparatus is relatively simple in construction and is of such a character that it may be safely exposed in garages and similar places without probability of damage by careless use of unskilled persons.

Various changes may obviously be made in the details of construction and inasmuch as I am the first to propose an apparatus which enables the inflation of automobile 105 tires from tanks containing air under pressure and with exact regulation of the pressure at which the air is delivered, I desire to claim my invention broadly and in every aspect, whether conforming exactly to the 110 present disclosure or different in details therefrom.

I claim:

1. In an apparatus for dispensing gas under pressure, the combination of an automatic pressure-reducing valve for varying the outlet pressure of gas passing therethrough, a dial, a manually adjustable indicator coöperating with the dial and operatively connected to the valve, and means 115 tending to hold said indicator in position to close said valve.

2. In an apparatus for dispensing gas under pressure, the combination of an automatic pressure-reducing valve for varying the outlet pressure of gas passing therethrough, a dial, a manually adjustable indicator coöperating with the dial and operatively connected to the valve, and resilient 120 means for returning the indicator to zero 130

position when released, to prevent the passage of gas through the valve.

3. In an apparatus for dispensing gas under pressure, the combination of an automatic pressure-reducing valve for varying the outlet pressure of gas passing therethrough, a dial, a manually adjustable indicator coöperating with the dial and operatively connected to the valve, means for 30 turning the indicator to zero position when released to prevent the passage of gas through the valve, and manually controllable means for holding the indicator in predetermined position.
5. 4. In an apparatus for dispensing gas under pressure, the combination of a manually adjustable indicator, means controlled by the adjustment of the indicator to permit the passage of gas at a predetermined pressure, and means to return the indicator to zero position when released.
- 10 5. In an apparatus for dispensing gas under pressure, the combination of a manually adjustable indicator, means controlled by the adjustment of the indicator to permit the passage of gas at a predetermined pressure, and means to return the indicator to zero position when released.
- 15 20 25

pressure, means to return the indicator to zero position when released, and manually controllable means for holding the indicator in a predetermined position.

6. In an apparatus for dispensing gas under pressure, the combination of a standard, a graduated dial on the standard, an adjustable indicator coöperating with the dial, the pressure-reducing valve actuated by 35 movement of the indicator for varying the outlet pressure of gas passing through the valve, and means for returning the indicator to zero position.

7. In an apparatus for dispensing gas under pressure, the combination of a standard, a graduated dial on the standard, an adjustable indicator coöperating with the dial, a pressure-reducing valve, means actuated by movement of the indicator for varying the 40 45 outlet pressure of the gas passing through the valve, means for returning the indicator to zero position when released, and means for holding the indicator in adjusted position.

In testimony whereof I affix my signature.
GREGORY JOHN SPOHRER.
